LOCOMOTIVE DRIVE UNIT

Winston A. Brecht, Forest Hills, and Frank L. Alben, Pittsburgh, Pa., assignors to Westinghouse Electric Corporation, East Pittsburgh, Pa., a corporation of Pennsylvania

Application July 28, 1943, Serial No. 496,408

7 Claims. (Cl. 105—113)

Our invention relates, generally, to locomotive driving units and, more particularly, to gear-drive units for turbine-driven locomotives.

In a turbine-driven locomotive it is necessary to provide a reduction gear unit for transmitting the torque developed by the turbines to the locomotive axles within the desired speed range. It is desirable that the gear unit housing be so supported in the locomotive frame that the reaction from the torque developed by the turbines can be transmitted to the frame in a simple manner and, at the same time, prevent transfer of any lateral forces of the wheel hubs to the drive unit housing. Since accuracy of alignment in the gearing is essential, the gear unit housing must be supported in such a manner that it is free from distortion. Also, since the gear unit is located between the side frames of the locomotive and underneath the boiler, it is essential that the unit be removable for overhauling when necessary.

An object of our invention, generally stated, is to provide an enclosed drive unit for a locomotive which shall be simple and efficient in operation and which may be economically manufactured and installed.

A more specific object of our invention is to provide a three-point support for the gear unit housing of a turbine-driven locomotive.

Another object of our invention is to provide removable supports for the gear unit housing of a turbine-driven locomotive.

A further object of our invention is to provide for adjusting the position of the gear unit housing in the frame of a locomotive.

Still another object of our invention is to provide stabilizing supports for the gear unit housing.

A still further object of our invention is to provide for limited radial movement of the gear unit housing.

Other objects of our invention will be explained fully hereinafter or will be apparent to those skilled in the art.

In accordance with one embodiment of our invention the front end of the gear unit housing for a turbine-driven locomotive is carried by a trunnion mounted in the locomotive frame and the rear end of the housing is supported at two points on opposite sides of a pivot pin in the locomotive frame, thereby permitting limited radial movement about the pivot pin.

For a fuller understanding of the nature and objects of our invention, reference may be had to the following detailed description, taken in

conjunction with the accompanying drawings, in which:

Figure 1 is a view, partially in side elevation and partially in section, of a portion of a locomotive structure embodying our invention;

Fig. 2 is a top plan view of the structure shown in Fig. 1;

Fig. 3 is an enlarged view, partially in side elevation and partially in section, of the front support for the gear unit housing;

Fig. 4 is an enlarged view, in side elevation, of the rear support for the gear unit housing;

Fig. 5 is an enlarged view, in front elevation, of the front support for the gear unit housing, and

Fig. 6 is a view, partially in side elevation and partially in section, of a modification of the front support for the gear unit housing.

Referring to the drawings, and particularly to Figs. 1 and 2, the portion of the locomotive structure shown therein comprises a locomotive frame 10 having side members 11 and 12 and cross members 13 and 14, and axles 15 having wheels 16 mounted thereon for supporting the locomotive frame. A gear unit housing 17 is provided for enclosing the gears, driving shafts, bearings and other elements of a locomotive drive suitable for transmitting the torque of the driving turbines (not shown) to the axles 15. A resilient drive of the type disclosed in the copending application of F. L. Alben, Serial No. 490,311, filed June 10, 1943, may be provided for each axle 15.

As explained hereinbefore, it is necessary that the gear unit housing 17 be properly supported in the locomotive frame and it is essential that the housing 17 be so mounted in the frame that the entire gear unit may be readily removed from the frame for maintenance and repair. The rear end of the housing 17 is supported by a two point support 18 and the front end is supported by a single point support 19.

As shown more clearly in Fig. 4, the rear support 18 comprises a horizontally extending plate 21 which is secured to the housing 17 and is disposed between a pair of horizontal arms 22 and 23 which are an integral part of a support member 24 that is removably mounted on the cross-member 13 of the frame 10. A removable pivot pin 25 is inserted through openings provided in the plate 21, the upper arm 22 and the lower arm 23 of the support member 24, thereby permitting limited radial movement of the gear unit housing about the pivot pin 25. The pivot pin may be secured to the support member 24 by a pair of tap bolts 26.

In order to provide the two points of support for the rear end of the gear unit housing, wearing pads 27 and 28 are provided on the bottom of the plate 21 and the top of the arm 23, respectively. The wearing pads are disposed on opposite sides of the pivot pin 25 and are spaced as far apart as possible on the plate 21. In this manner, the rear end of the gear unit housing is supported at two points which are in the same horizontal plane and are located on opposite sides of the pivot pin 25 which is on the longitudinal center line of the gear unit housing.

The support member 24 is so constructed that it can be removed from the frame 10 by removing the pivot pin 25 and bolts 29 which secure the member 24 to the frame. In this manner the rear end of the housing 17 may be dropped between the side frames of the locomotive when it is desired to remove the gear unit. A pair of keys 31, which are secured in position by tap bolts 32, is provided to prevent shearing of the bolts 29 which hold the support member 24 on the cross member 13 of the frame.

In order to provide for vertical adjustment of the rear end of the housing 17, shims 33 are disposed between the support member 24 and the cross member 13 of the frame. In this manner, the housing 17 may be properly aligned with the axles of the locomotive, thereby permitting satisfactory operation of the driving gears.

As shown more clearly in Figs. 3 and 5 the support 19 for the front end of the gear unit housing 17 is of a trunnion type which is free to adjust itself for longitudinal expansion. The front support 19 comprises a trunnion member 35 which is disposed in a depression in the cross member 14 of the frame and is provided with a pair of laterally extending ears 36 which rest on the cross member 14. As shown in Fig. 3, a plate 37, which may be welded to a cross member 38 of the gear unit housing 17, is bored for receiving a round pin 39 on the trunnion support 35. A bushing 41 may be disposed in the plate 37 to provide a bearing for the trunnion pin 39. An opening 42 may be provided in the cross member 38 to permit longitudinal movement of the gear unit housing on the trunnion pin 39.

In order to permit vertical adjustment of the front support 19, shims 43 may be provided between the ears 36 and the cross member 14. The trunnion support 35 may be removed to permit the front end of the gear unit housing 17 to be dropped between the side frame members by removing bolts 44 which secure the member 35 to the cross member 14. Thus both the rear support 18 and the front support 19 may be removed to permit removal of the gear unit housing 17 from the locomotive frame.

In order to prevent swaying of the gear unit housing, particularly when the locomotive is rounding curves, a stabilizing support 45 is provided on each side of the locomotive frame at the rear of the housing 17. As shown in Fig. 2 the stabilizing members 45 are of a T-shape. One end of each member is secured to the lower portion of the side frame by bolts 46. The members 45 extend horizontally to slidably engage the sides of the housing 17, thereby preventing any side sway of the gear unit.

In the modification of the invention shown in Fig. 6, the front support 19 for the gear unit housing 17 is lowered in the cross frame 14 sufficiently to place the front support substantially on the same horizontal plane as the axles 15. The front support shown in Fig. 6 comprises a trunnion sup-

port 51 having a round portion 52 disposed in an opening provided in a plate 53 secured to the front end of the gear unit housing 11. The trunnion support 51 is removably secured to the cross member 14 by bolts 54. It may be removed from the cross member 14 in the manner hereinbefore described to permit the front end of the gear unit housing to be lowered between the side frames of the locomotive.

In the event that it is desired to remove only the lower portion of the gear unit housing 17 a projection 55 is provided on the upper portion of the housing to permit a block to be inserted between the projection 55 and the frame of the locomotive thereby supporting the upper portion of the gear unit housing. By lowering the location of the front support in the locomotive frame, a more stable support for the gear unit is provided.

From the foregoing description it is apparent that we have provided a three-point support for a gear unit housing which is so constructed that a portion or all of the gear unit housing may be removed from the frame when desired. The elevation of the housing may be adjusted in a vertical plane to secure proper alignment in the locomotive frame. Provision is made for limited radial movement of the housing in the frame, thereby preventing a distortion of the locomotive frame. Stabilizing means are also provided for keeping the housing in a stable condition at all times.

Since numerous changes may be made in the above described construction and different embodiments of the invention may be made without departing from the spirit and scope thereof, it is intended that all matter contained in the foregoing description or shown in the accompanying drawings shall be interpreted as illustrative and not in a limiting sense.

We claim as our invention:

1. In a locomotive drive, the combination with a frame having side and cross members and axles for supporting the frame, of a gear unit housing disposed between said side frame members and a pair of said cross members, means on one of the cross members for supporting the housing at one point, means on the other cross member for slidably supporting the housing at two points, said two points of support being in the same horizontal plane, and a pivot pin disposed between said two points of support to permit movement of the housing about the pivot pin in a horizontal plane.

2. In a locomotive drive, the combination with a frame having side and cross members and axles for supporting the frame, of a gear unit housing disposed between said side frame members and a pair of said cross members, means on one of the cross members for supporting the housing at one point, means on the other cross member for slidably supporting the housing at two points, said two points of support being in the same horizontal plane, and a pivot pin disposed between said two points of support to permit movement of the housing about the pivot pin in a horizontal plane, said pivot pin and said single point of support being on the longitudinal center line of the housing.

3. In a locomotive drive, the combination with a frame having side and cross members and axles for supporting the frame, of a gear unit housing disposed between said side frame members and a pair of said cross members, means on one of the cross members for supporting the housing at one point, means on the other cross member for slidably supporting the housing at two points, said

two points of support being in the same horizontal plane, and a pivot pin vertically disposed between said two points of support to permit radial movement of the housing about the pivot pin.

4. In a locomotive drive, the combination with a frame having side and cross members and axles for supporting the frame, of a gear unit housing disposed between said side frame members and a pair of said cross members, a trunnion mounted on one of said cross members for supporting one end of the housing, means mounted on the other cross member for providing two points of support for the other end of the housing, said two points of support being in the same horizontal plane, and a pivot pin vertically disposed between said two points of support and removably secured to said supporting means to permit radial movement of the housing about the pivot pin.

5. In a locomotive drive, the combination with a frame having side and cross members and axles for supporting the frame, of a gear unit housing disposed between said side frame members and a pair of said cross members, a trunnion mounted on one of said cross members for supporting one end of the housing, means mounted on the other cross member for providing two points of support for the other end of the housing, said two points of support being in the same horizontal plane, a pivot pin vertically disposed between said two points of support to permit radial movement of the housing about the pivot pin, and means for adjusting said trunnion and said supporting means in a vertical plane, said trunnion being

disposed to permit longitudinal expansion of the housing.

6. In a locomotive drive, the combination with a frame having side and cross members and axles for supporting the frame, of a gear unit housing disposed between said side frame members and a pair of said cross members, a trunnion mounted on one of said cross members for supporting one end of the housing, means mounted on the other cross member for providing two points of support for the other end of the housing, said two points of support being in the same horizontal plane, and stabilizing means attached to said side frame members for slidably engaging the sides of said housing to permit vertical movement but prevent side-swaying of the housing.

7. In a locomotive drive, the combination with a frame having side and cross members and axles for supporting the frame, of a gear unit housing disposed between said side frame members and a pair of said cross members, a trunnion mounted on one of said cross members for supporting one end of the housing, means mounted on the other cross member for providing two points of support for the other end of the housing, said two points of support being in the same horizontal plane, and stabilizing means attached to said side frame members for slidably engaging the sides of said housing, said stabilizing means being disposed in a different horizontal plane from said two points of support to permit vertical movement but prevent side-swaying of the housing.

WINSTON A. BRECHT.
FRANK L. ALBEN.
